UNITED STATES PATENT OFFICE.

CHARLES A. COOK, OF CHICAGO, ILLINOIS, ASSIGNOR TO C. H. D. ELECTRIC COMPANY, OF CHICAGO, ILLINOIS, A CORPORATION OF ILLINOIS.

ELECTRIC FLATIRON.

Application filed October 30, 1922. Serial No. 597,772.

To all whom it may concern:

Be it known that I, CHARLES A. COOK, a citizen of the United States, residing at Chicago, in the county of Cook and State of Illinois, have invented certain new and useful Improvements in Electric Flatirons, of which the following is a specification.

My invention relates to electric flat irons and contemplates, broadly, an improved electric flat iron to be used in conjunction with an automatic switching means for causing energy to flow into the heating element of the iron, when desired.

My invention has for one of its objects 15 the provision of mechanism for performing the ironing of clothes, etc., with the least encumbrance owing to the absence of electric cords which have heretofore been continuously connected directly to the iron, 20 when the iron was being used.

A further object is that the operator is never in danger of receiving a shock because there is no energy flowing into the iron when in use.

25 My invention will be better understood by reference to the accompanying drawing, in which,—

Figure 1 is a top view of the stand showing certain features of my invention.

30 Figure 2 is an elevation view of the parts shown in Figure 1, with some of the mechanism shown in cross section.

Figure 3 is a view similar to Figure 2, and showing a flat iron in place, and the 35 electric energy flowing through the heating element of the iron.

Figure 4 is a sectional view taken on line 4—4 of Figure 2.

Figure 5 is a partial end view of the flat 40 iron, showing the two terminal springs which are connected to the heating element.

The flat-iron stand comprises a plate 6 provided with a forward support 7 and side supports 8—8; said supports 8—8 extend 45 above the plate 6 a short distance and provide means in conjunction with the lug 9, which is recessed at 10, to facilitate the placing of the electric flat iron 11.

When the flat iron is placed upon the 50 plate, a switch 12 is automatically closed so as to include the heating element 13 in circuit. This switch is preferably made of two metallic switch blades 14 and 15 separated by a block of insulation 16 and pivoted by pins or screws 17 and 18 to the side

walls 19 and 20, respectively, also of insulating material, such as hard rubber or fiber. A top connecting wall 21 carries a central partition 22, which is also of insulating material, which serves to provide 60 slots through which the blades 14 and 15 swing. The blades 14 and 15 are connected by means of an insulation pin 23, to which one end of a helical spring 24 is fastened, the other end of which is secured to 65 a rear wall 25 of the housing for the switch. Normally the switch is held in a retracted position, as shown in Figure 2, with contacting faces 26 and 27 of the switch blades 14 and 15, respectively, drawn back so as to 70 prevent accidental bridging of the two blades. In this position, the upturned portion 28 of the block 16 projects above the surface of the plate 6 and is in position to be depressed by the use of the flat iron 11. 75 The plate 6 is formed with a protecting housing 29 below the switch 12.

When the user of the flat iron places it upon the plate 6, the pointed or forward part of the iron is first inserted in the recess 10 and then the rear part is dropped between the lugs 8—8 and into contact with the portion 28, which causes the contacting faces 26 and 27 of the blades 14 and 15 to swing into engagement with the terminal 80 springs 32 and 33 carried on an insulating block 34 on the flat iron, these springs being connected to the terminals of the heating element 13. Since the blades are suitably connected by leads 35 and 36 to a source 90 of energy 37, the element 13 and the flat iron will be electrically heated to a suitable temperature.

My invention provides a flat iron and a simple means for causing an automatic electric connection to be made to the flat iron in order to heat the same, and obviates the necessity of turning the iron on end during the short intervals of non-usage, as is customary. The user is also not encumbered by electric cords, which often interfere with proper employment of an electric flat-iron.

It is apparent that changes and modifications can be made without departing from 105 the spirit and scope of my invention.

I claim:

1. In combination, an electric flat iron having two terminals, a heating stand therefor, a switch rotatably supported on a sta- 110

tionary part of said stand and comprising two blades having contact ends adapted to engage said terminals, a member rigidly secured to said blades and normally positioned 5 to be engaged by the bottom surface of the flat iron placed on the stand, whereby said switch is rotated and said blades caused to engage said terminals.

2. In combination, an electric flat iron 10 having two terminals, a heating stand therefor, a switch on said stand, said switch comprising two blades arranged side by side and pivotally supported intermediate their ends on a stationary part of said stand, the 15 upper ends of said blades being movable into contact with said terminals as the blades are rotated about their point of pivotal support, a member rigidly secured to the lower ends of said blades and normally positioned

20 to be engaged and moved by the bottom surface of a flat iron placed on said stand, whereby said blades are automatically rotated into engagement with said terminals.

3. In combination, an electric flat iron 25 having two terminals, a heating stand therefor having a surface on which the bottom of the iron is adapted to rest, a switch rotatably supported on a stationary part of said stand and comprising two blades having 30 their upper ends arranged to engage said terminals as said switch is rotated, a member rigidly secured to the lower ends of said blades, said member extending forwardly of said blades and having a part normally positioned above said surface on the stand and 35 in position to be engaged by the bottom surface of the flat iron placed on the stand,

whereby said blades are automatically rotated into engagement with said terminals.

4. In combination, an electric flat iron 40 having two terminals, a heating stand therefor, a switch rotatably supported on a stationary part of said stand and comprising two blades having contact ends adapted to engage said terminals, a member rigidly secured to said blades and normally positioned 45 to be engaged by the bottom surface of the flat iron placed on the stand, whereby said switch is rotated and said blades caused to engage said terminals, and yieldable means 50 for maintaining said member in position to be engaged by the iron placed on the stand.

5. In combination, an electric flat iron having two terminals therein, a heating stand therefor having a surface upon which 55 the bottom of the iron is adapted to rest, a casing on said stand, a switch arranged in said casing and rotatably supported on a stationary part of said stand, said casing having an opening for each of said blades, 60 said blades having contact portions on their upper ends adapted to be moved through said openings and into engagement with said terminals as said switch is rotated, a member rigidly secured to the lower ends of 65 said blades and having a part normally positioned above said surface on the stand and in position to be engaged by the bottom surface of the flat iron placed on the stand, whereby said switch is rotated and said 70 blades automatically brought into contact with said terminals.

CHARLES A. COOK.
